UNITED STATES PATENT OFFICE.

MILTON T. WESTON, OF ORANGE, NEW JERSEY.

ELECTRICAL PRINTING APPARATUS.

No. 904,743.

Specification of Letters Patent.

Patented Nov. 24, 1908.

Application filed September 25, 1901. Serial No. 76,544.

To all whom it may concern:

Be it known that I, MILTON T. WESTON, a citizen of the United States, residing at Llewellyn Park, city of Orange, county of 5 Essex and State of New Jersey, have invented certain new and useful Improvements in Electrical Printing Apparatus, of which the following is a specification.

This invention relates particularly to typewriters, and generally to any case where character impressions are to be produced successively on a suitable impression-receiving surface.

The object of my invention is to enable the 15 character impressions to be effected more rapidly.

My invention has other advantages of simplicity in construction and operation, and adaptability to different applications, as 20 will hereinafter appear.

An important feature of my invention is a distributor and selecting device, this distributor and selecting device having a rapid continuous movement and carrying a plurality of electro-magnetic devices brought 25 successively into connection with the line or controlling circuit, and each of such electro-magnetic devices controlling the operation of a corresponding trip device, said trip devices in turn controlling local circuits to 30 perform certain functions. The selecting electromagnetic devices are preferably mounted on a continuously rotating carrier, and while each of such devices is in connection 35 with the controlling circuit for a small fraction of a revolution, the device that is tripped thereby may have the greater part of a revolution in which to operate. This trip device controls the printing and other 40 local operations, and the time required for it to perform its functions is considerably greater than the time required to operate the trip device, so that the rotating selecting device may move at much greater speed 45 than if the electromagnetic devices had to perform these functions directly.

Another feature of my invention lies in the impression means. The trip devices referred to constitute type levers or impression hammers that when released assume positions wherein they will, in the revolution of the carrier, strike the paper on the platen, and, on so striking the paper, said type levers are thrown back by their recoil into 55 normal position.

My invention might be applied to a print-

ing telegraph in which case I would employ a receiving instrument which revolves continuously at a comparatively high rate of speed, producing the message in printed 60 form upon a strip, page or telegraph blank and a transmitting instrument which also revolves continuously in synchronism with the receiver and sends out electrical pulses at predetermined intervals, one pulse for each 65 letter, said pulses being either positive or negative, or all of one polarity.

Figure 1 is a front elevation of my receiving instrument, the base being shown in section. Fig. 2 is a transverse vertical section 70 view on the line *a—a* of Fig. 1. Fig. 3 is a longitudinal vertical section along the axis of the receiver cylinder. Fig. 4 is a transverse sectional view on the line *c—c* 75 of Fig. 3. Fig. 5 is a sectional rear view of the receiver showing the carriage operating mechanism. Fig. 6 is a plan view of carriage operating mechanism and inking device. Fig. 7 is a sectional side elevation of same taken on the line *c—c* of Fig. 6. Fig. 8 is a plan view of the carriage. Fig. 9 is a sectional elevation of a "ball ratchet" for 80 operating the platen. Fig. 10 is a vertical section of same. Fig. 11 shows a slight modification of the retaining spring latches 85 for the type levers, from that shown in Fig. 4. Fig. 12 is a partial plan view showing arrangement of type bars or levers, spring latches and magnets in the modification 90 shown in Fig. 11. Fig. 13 is a partial vertical longitudinal section through the receiver showing modification in the magnet arrangement. Fig. 14 is a vertical section on the line *d—d* of Fig. 13. Figs. 15 to 17 show a typewriter embodying my invention, 95 the keyboard and distributor of the transmitter being combined with the selecting device of the receiver to form a single instrument, and the synchronizing device being omitted. Figs. 18 to 21 show a modification 100 in the magnetic tripping device. Figs. 22 to 24 show as a further modification, a mechanical tripping means. Figs. 25 and 26 show diagrammatically the local circuits for 105 operating the carriage mechanism of the printer and for synchronizing the receiver.

The telegraph receiver (Figs. 1 to 10) comprises a suitable base 1, with standards 2 projecting therefrom, in which is journaled the shaft 3 of the distributing and selecting cylinder 4. On one end of the shaft 3 is attached the armature of a motor 5, for

rotating the shaft, and on the other end the armature of a motor 6 for synchronizing the shaft with the shaft of the transmitter. Motor 5 is operated by a local battery circuit 5^a. The body of cylinder 4 is preferably of insulating material and carries at one end a set of commutator segments 7 and contact rings 8, 9, 10, 11, and at the other end a set of commutator segments 7', and contact rings 8', 9', 10', 11'. This cylinder also carries, by disks 12, 12', fastened thereto, two sets of selecting magnets 14, 14', and for each magnet is provided an armature 15 or 15' that is preferably formed as a spring plate of magnetic material, fastened at one end to the cylinder 4. These spring armatures are oppositely polarized in the two sets 15, 15', so that the armatures of one set will respond to impulses of one polarity only, while those of the other set respond to opposite impulses. Adjacent to the two sets of armatures 15, 15' are the two sets of trip devices, mounted in disks 13, 13, 13', 13', on cylinder 4, each trip device comprising a central body portion 16, 16' pivoted in the said disks and having at one end the type arm or hammer 17 or 17' and at the other end the trip arm 18 or 18', engaging normally under a hook 15^a of the corresponding armatures 15, so that the armatures 15 act as latches to hold the respective trip devices in normal position, with their type-levers or hammers 17 or 17' lying in their innermost position as shown at the bottom of Fig. 3. All of the arms 17, 17' are weighted at the outer end so that the centrifugal force resulting from the rapid rotation of the cylinder or carrier 4, will tend to throw these arms outwardly to the position shown at top of Fig. 3 for an arm 17. Some of these arms 17, 17' constitute type levers, the weighted part or head 17^a carrying the type characters, and the trip devices being angularly arranged so that the type levers strike at the same point on the platen indicated at 49, while other arms are blank or free from characters. All of these trip devices are adapted to act as circuit closers for local circuits, contacts 16^a on the body or pivot portion thereof being adapted to contact with terminals 19, 19' in the insulating cylinder body 4, arranged in pairs for the respective trip devices. Each trip device is normally out of contact with the terminals 19 or 19', but when the trip device is released and is turned by the movement of its arm, say 17, to outer position, shown at top of Fig. 3, the trip device bridges their contacts and closes a local circuit or circuits connected thereto. A cushion ring 13^a is arranged on cylinder 4 in position to receive the recoil impact of the hammer arms 17 or 17' and prevent noise and wear.

The circuit connections of the receiver are shown in Figs. 1, 3, the main line 20 being connected to terminals or brushes 21, 21'

bearing on the commutator segments 7, 7' from which connections 22, 22' lead to the respective magnets 14, 14', each segment being connected to a corresponding magnet, and from said magnets to the collector rings 8, 8', and through brushes 23, 23', bearing thereon to "ground". Thus the main line is simultaneously connected to two magnets 14, 14', one on each side, and as the armatures of these magnets are oppositely polarized, an impulse coming over the line will affect one or the other of these armatures according to the nature of the impulse, whether positive or negative. In the rotation of the shaft 3, the commutator segments 7, 7' constitute distributors whereby the pairs of magnets 14, 14' are brought successively into connection with the line 20, so that as an impulse comes over the line it will operate some particular one of the magnets 14 or 14' depending on the rotative position of the cylinder 4 at that time, so that if the cylinder rotates in synchronism with the transmitter, the selection of the magnet 14 or 14' will be controlled by the transmitter.

Local circuits are provided in the receiver for operating the carriage mechanism of the printer and for synchronizing the receiver. A battery 27 energizes all these local circuits, a circuit 26, 26' leading from this battery to a pair of spring contacts 28, 29 on one side of the machine, bearing on a pair of contact rings, 9, 10, from which wires 30 lead to all the pairs of terminals 19 or 19' on both sides of the machine, that correspond to character-selecting and word space controlling trip devices, indicated at x—x. In this circuit 26, 26' is included the magnet 25 that controls the step by step carriage feed. (See also Fig. 5.) One trip device marked y in Fig. 25 on one side of the machine is appropriated to the carriage return operation and the corresponding pair of terminals 19', is connected by wires 31 to rings 9', 10', and thence by spring contacts 28', 29' and circuit 33, 26, to the magnet 34 that controls the return of the carriage, the wire 26 being a common return for both of these local circuits.

The local mechanism controlled by the local circuits 26', 26, 33, 26, and controlling the platen feed along the line and from line to line, (Figs. 2 and 5 to 9) comprises a carriage 35 moving by its rolls 36 on fixed guides 37, and a rack 38 on said carriage engaged by a gear 39 on a shaft 39 actuated by a spring 40 to drive the carriage in one direction. A ratchet rack 41 is also attached to carriage 35 and is engaged by an operating pawl 42 carried by the armature lever 43 of the feed magnet 25 so that on each closure of the local circuit 26', 26, the carriage will be moved forward one step, a retaining pawl 44 holding the rack in advance position when the armature lever is again retracted by suitable means. In order to return the carriage

automatically at the end of a line, a trip device is provided, consisting of an armature lever 45 for magnet 34, said lever 45 engaging with pins on both of the pawls 42, 44, 5 upon energization of magnet 34 to disengage said pawls from rack 38 and allow the carriage to be returned by its spring 40. A latch 45^a serves to hold this releasing armature in position to free the carriage until 10 the latter reaches the starting point when a pin 35^a thereon strikes latch 45^a and releases the armature arm 45, permitting the pawls 42, 44 to reengage the carriage rack. As the carriage approaches the starting 15 point, an arm 47^a on a feed device 47 on the platen shaft engages a fixed slotted cam device 48 which serves to turn the platen one step for feeding from line to line. The feed device 47 preferably consists of a ring embracing a disk 49^a on the platen shaft, and a 20 ball clutch 47^b in said ring and engaging with said disk.

An inking means is provided, consisting of a roll 50 of felt or other suitable material, 25 containing ink and located in position to roll against the faces of the type characters in the rotation of the carrier 4 when the type devices are in inner or normal positions, the roll 50 being rotated by the contact of the 30 type.

To synchronize the receiver with the transmitter I provide the motor or electromagnetic device 6, and an electromagnetically operated switch, adapted to close the circuit 35 to said motor periodically, say once in each revolution, so as to aid or resist the rotative effect of the main motor 5. The system of circuits for synchronizing is shown in Fig. 26 and comprises a local battery 51 for operating the motor 6, a reversing switch or pole 40 changer 52 for reversely connecting said battery through circuit wires 53 with the armature of said motor, two magnets 54, 54' operating reversely on said switch. The local 45 battery is connected through said magnets to brushes 56, 56' bearing on the collector rings 11, 11' on opposite ends of the cylinder 4, these rings being connected with a terminal 19 or 19' on each side of the machine, adapted 50 to be connected with a corresponding terminal 19 or 19' by one or the other of a particular pair of the trip device circuit closers 16, 16', such other terminals 19 or 19' being connected to the respective rings 10, 10' from 55 which the connection 26, above referred to, leads back to the battery 27. These special trip devices are indicated at α — α in Fig. 26. At the moment or portion of the revolution that is appropriated to synchronizing, the 60 transmitter sends over the line two successive impulses, of opposite polarity, and at this time the contacts 7, 7' on the receiving distributor which are engaging the brushes will be those which are connected to the particular pair of magnets 14, 14' that control

through these trip devices α — α the local magnets 54, 54', above referred to. There is a slight interval between these opposite impulses, and if the receiver is in synchronism, the interval will correspond to the time 70 elapsing between the contact of brush 21 with the commutator segment 7 leading to magnet 14 and the contact of brush 21' with the commutator segment 7' leading to magnet 14', so that no current is sent to the magnets 54 and 54' and the switch 52 is not operated, but if the receiver lags, it will receive a portion of the second synchronizing impulse which will operate the electromagnet 14 on one side, closing the local circuit to one 75 of the pole changer magnets, say 54, and sending a circuit through the armature of the synchronizing motor so as to accelerate the receiver. The synchronizing motor thus acts concurrently with the driving motor 5, 80 to accelerate or to retard the carrier shaft, as may be required. If the distributor then gains in speed so as to run ahead of the transmitter, the opposite effect takes place. 85 In starting, the switch 52 will be set for acceleration, so that the receiver will run up to speed and will then be checked, the pole changer throwing the impulses through the armature to accelerate or retard as may be required. As shown in Fig. 26, the transmitting tape is narrower than the space between the particular contacts 69^a which send current to the synchronizing magnets, so that 90 this synchronizing operation is not affected by the tape and takes place in the same manner whether tape or keyboard transmission be used.

The impulses that come along the line operate the receiver in the following manner. At the time this impulse is received, some 105 one pair of contacts 7, 7' is in contact with the fixed line contacts 21 and 21' and the corresponding magnets 14, 14' are therefore in connection with the line, so that the impulse received will energize both of these 110 magnets, but on account of the opposite polarity of the armatures 15, 15', only one, say 15', will be attracted, and the corresponding trip device will be released. The current passes through the receiver as follows: From 115 line terminal 21 or 21' through contact 7 or 7' to a magnet 14 or 14' therein by wires 22 or 22' to ring 8 or 8' and by contact 23 or 23', to earth, returning to the other pole of battery 81 or 81'. As soon as released, the trip device will be moved by centrifugal action to its outer position, the weighted end traveling in the path indicated by dotted lines in Fig. 2. 120 As the carrier 4 continues to rotate thus, it will eventually carry the weighted arm 125 which has been thus projected, forcibly against the platen 49 or against the paper impression receiving surface thereon. This arm in the case of most of the trip devices, carries a printing type so that the trip de- 130

vice acts as a character-selecting means, and by its impact against the paper will effect the impression. The type lever 17' then immediately rebounds by the effect of the blow 5 on the platen, and flies back to normal position close to the cylinder and is caught and held by the latch device. The type are kept continually inked by roll 50 so that when they strike the paper they will print the corresponding character thereon. The operation 10 of the trip device 16 as above described, results in closing the local circuit of the carriage feed magnet 25, and the carriage is moved forward one step.

15 One or more of the trip devices is appropriated to word spacing and has no type but controls the spacing magnet 25 like the other trip devices. In Fig. 3 I have shown the two blank trip devices at the bottom, and one 20 may be assumed to be a spacing device and the other the carriage return device.

It will be noted that the impression is effected by a blow delivered substantially perpendicular to the platen or impression surface, giving a sharp impression and capacity for manifolding. I believe that this effect 25 with a continuously rotating type carrier is new and it combines the advantage of strong and sharp impressions, with extreme rapidity of operation, the latter being limited only by the speed of rotation. It will also be noted that during any one rotation of the distributor and selecting cylinder 4, the number of characters selected may be one, 30 two or more, according to the sequence in which the characters are selected by the transmitter, and the order in which they occur on the type carrier. This is true even if only one complete alphabet be used in the 35 type-carrier, in practice, the more frequently occurring letters, such as "e" and "t", may be distributed in several places on the type carrier, so as to still further increase the number of impressions that may be made 40 during a single rotation.

Various modifications may be made in the construction of the apparatus without departing from my invention. Thus in applying the invention to a typewriter the key 45 board and distributor of the transmitter may be combined with the selecting devices of the receiver to form a single instrument and the synchronizing devices would of course be omitted. In Figs. 15 to 17 I have shown 50 such an embodiment of my invention, the distributing cylinder 4, contact rings 8, 9, etc., and two series of selecting magnets 14, 14' are arranged as above described, the whole being supported on a suitable base 1, 55 but the commutator segments 68 which are connected respectively to the magnets 14, 14', are arranged in spiral order to contact 60 respectively with a series of contact springs 69 controlled by a plurality of keys 82 65 through intermediate impact or momentum

devices 83 and spring retainers 84 as above described in connection with the transmitter. The respective spring contacts 69 are reset after each operation by the magnet 89, in a local circuit controlled by the trip devices 70 91, 91', which are in this case arranged in two sets and controlled respectively by the two sets of magnets 14, 14'. A motor 5 is provided for driving the cylinder 4. The synchronizing devices and main circuit are 75 omitted, and the local devices for feeding the carriage may be the same as above described for the receiver. In the operation of the keyboard mechanism of this typewriting machine, the impulses transmitted 80 through the contacts 69, 68, will pass directly to the corresponding magnets 14 or 14' and through the trip devices controlled thereby, selectively print the proper characters and control the several resetting and 85 feeding operations.

Figs. 11 and 12 show a modification of the latch spring or selecting armatures that control the trip devices. In place of having two rows of such armatures and magnets, as 90 in Fig. 1, I have provided a single row, each armature being double, as shown at 15, 15', with oppositely polarized parts so that one or the other part of the armature is attracted according to the direction of the pulse 95 through the magnet 14. Two trip devices are shown for each magnet 14, engaging by the arms 18, 18' with the hooks of respective parts of the corresponding latch armature so that one or the other trip device of a pair 100 will be released according to the polarity of the controlling impulse.

In some cases I may mount only the trip devices 15, 16, 17, 18 on the rotating cylinder or carrier, and arrange the electro-magnetic 105 controlling means in fixed position on the machine, as shown in Figs. 13 and 14. In this case only one magnet 14 is required, the latch armatures 15 coming necessarily opposite same in the rotating of the carrier, so 110 that the selection of the trip device operated depends on the time that the impulse passes in the controlling circuit, and by making the spring latch armatures 15 of alternately opposite polarity, the selection may also be 115 made to depend on the direction of polarity of the impulse.

Instead of depending on centrifugal action for the operation of the trip devices, 120 springs may be used to effect a similar result, and the movement in that case need not be radial. Moreover the tripping of the devices may be effected by mechanical instead of electro-magnetic means. Thus in Figs. 22 to 24 I have shown pins 110 sliding in a fixed 125 frame 1' and operated by keys or by any suitable means, these pins being pressed to normal position by springs 110' and engaging when operated with tappets or lugs 111' on radial shafts 111, each being acted on by 130

a spring 112 to hold the lug 111' in position to engage the corresponding spring 110 when the latter is pressed by the operator. The respective lugs 111' are at different distances from the center of the shaft 3 carrying the wheel 4' in which the radial shafts 111 are mounted, and the pins 110 are located at corresponding distances from said shaft so as to engage only the corresponding lugs. Each shaft 111 has also a lug or arm 111'', engaging an arm or a trip device on shaft 116 pivoted in radial position on wheel 4' and impelled by a spring 116' so as to turn in a direction transverse to the radial shaft, therefore by bringing its hammer arm 117^a in position to impinge on the platen roll 49 in the rotation of wheel 4', the rebound from said platen causing the device 117^a, 116 to be restored to normal position, in which it is caught and held by the latch device 111, 111'. It will be noted that the movement of the impression device in this instance is not radial to the axis of the carrying means, but is tangential or transverse to the radial direction, as it does not depend on centrifugal force.

Although the latch armature and trip device is advantageous as giving a quick and sensitive action, I consider it within my invention to use electro-magnetically controlled selecting devices of any nature rotated with the carrier and brought successively into position or condition to be controlled by the controlling circuit. Thus these devices may be simply armature devices held in by springs and drawn out by their magnets (or vice versa) to position in which they will strike the platen or perform other functions.

Figs. 18 and 19 illustrate a form wherein the series of magnets 14^c operate to hold the impression devices in inoperative position, through their armatures 15 which are formed as arms on the shafts 16 of the impression devices, and are included in local circuits 119 normally closed by contact springs 120, acting as armatures for another series of magnets 14 which are connected through the commutator segments 7 and ring 8 with the controlling circuit, similarly to the magnets 14 in Fig. 1. The said local circuits 119 are connected through the magnets 14^c to a collector ring 121, while the contact springs 120 contact with a collector ring 121', these collector rings being connected through fixed spring contacts with a battery 123. When any magnet of the series 14, is operated as above described in connection with Fig. 1, it opens a local circuit at 120, 121' and the corresponding magnet 14^c is deenergized allowing its impression device controlled thereby to fly out to operative position.

In Figs. 20 and 21 is shown a form wherein the magnets operate to draw the impression devices 17^a into operative position, springs 116' acting on the shafts 16 of the impression devices serving to normally hold

the same in inoperative position, while armatures 15 on said shaft 16 are pulled by the magnets 14 to move the impression devices into printing position when the magnet is energized.

I have described in this application the construction and operation of an electric receiver for telegraphs, because the same is in the main similar to the electric typewriter, but the right is reserved to claim the receiver for electric telegraphs in a subsequent application.

Having thus described my invention, the following is what I claim as new therein and desire to secure by Letters Patent:—

1. In a printing apparatus, a plurality of electro-magnetically controlled trip devices, a continuously moving carrier on which said devices are mounted, and printing means controlled by said trip devices.

2. In a printing apparatus, a continuously moving carrier, a plurality of electro-magnets and trip devices operated thereby and mounted on said carrier, printing means operated by said trip devices, distributor contacts on said carrier, and a controlling circuit and terminals coöperating therewith to connect the electro-magnets successively with the controlling circuit.

3. The combination of the continuously moving carrier, a plurality of electro-magnets and trip devices for the purpose described and operated thereby, mounted on said carrier, a controlling circuit and distributor contacts putting said electro-magnets successively in connection with said controlling circuit.

4. In a printing apparatus, a plurality of electro-magnetically controlled trip devices, a carrier on which said devices are mounted, means for moving said carrier and printing means controlled by said trip devices.

5. The combination with the continuously rotating carrier, and a plurality of devices pivotally mounted thereon; of weights disposed upon said devices in such positions as to cause the carriers to tend to fly outward by centrifugal force during the rotation of said carrier, means for holding said devices inwardly against the influence of said weights, and means for returning said devices to inward position.

6. The combination with the platen, the rotary carrier having its axis of rotation parallel with the axis of said platen, and a plurality of printing devices pivoted to said carrier; of weights disposed on said printing devices at such positions as to cause the devices to tend to move outward by centrifugal force into positions wherein the rotation of the carrier will cause them to impinge on the platen by direct impact substantially perpendicular to the platen surface and rebound inwardly away from striking position.

7. In a printing apparatus, the combination with the continuously rotating carrier, of a plurality of type levers pivoted thereon and tending to swing outward by centrifugal force, latch devices for holding said type levers from outward movement, electro-magnetic controlling means for said latch devices, and a platen coöoperating with the type levers when they are in their outer position. 10
8. In a printing apparatus, the combination with the continuously rotating carrier, of a plurality of type levers pivoted thereon and tending to swing outward by centrifugal force, armature latch devices for holding said type levers from outward movement, a plurality of magnets mounted on said carrier and controlling said armature latch devices, a distributor placing said magnets successively in connection with a controlling circuit, and a platen coöoperating with the type levers when in their outer position. 15
9. In a printing apparatus, the combination with a platen, of a rotatable carrier, a character impression device pivoted on said carrier and having a tendency in the rotation thereof to move into a position in which it will strike the platen or the impression surface thereon, means for holding said impression device out of coöperating relation with the platen, and means for releasing said holding means. 20
10. In a printing apparatus, the combination with the platen, of a rotatable carrier, a series of character impression devices pivoted on said carrier and adapted, in the rotation of the carrier, to move into positions in which they will strike the platen or the impression surface thereon, a series of latch devices for holding said impression devices out of coöperating relation with the platen, a controlling circuit and electro-magnetic means controlling said latch devices and putting the same successively under the control of said circuit. 25
11. In a printing apparatus, the rotating carrier, trip devices carried thereon comprising type carrying devices and blank devices, means for selectively operating said trip devices, a platen, and feeding means therefor controlled by said trip devices. 30
12. In a printing apparatus, a rotating carrier, character-selecting devices mounted thereon, blank space-selecting devices also mounted thereon, said character-selecting and blank space-selecting devices having a tendency to move from a normal to abnormal position when released, a platen coöperating with all said devices to return same to normal position, means for holding the said devices in normal position and feed-controlling mechanism for said platen controlled by both character-selecting and blank space devices when in abnormal position. 35
13. In a printing apparatus, a platen, a rotating carrier, character-selecting devices, blank space-selecting devices and platen return controlling devices, all mounted on said carrier, means for selectively operating said devices, and means controlled by the character and blank space-selecting means when in operated position to feed the platen, and means controlled by the platen return controlling device when in operated position, 70 to return the platen. 75
14. In a printing apparatus, a platen, a rotating carrier, character-selecting devices, blank space-selecting devices, and platen return controlling devices, also blank, all 80 mounted on said carrier, electro-magnetic means for selectively operating said devices, circuit controlling devices mounted on the carrier and controlled by the respective devices aforesaid, and platen feeding and return magnets and circuits, connected with said controlling devices to feed the carriage on the operation of a character or blank-space-selecting devices, and to return the platen on the operation of a platen return 85 controlling device. 90
15. In a printing apparatus, the combination with the platen; of a rotating carrier and a type lever pivoted on said carrier and having its weight so disposed relatively to its pivot as to cause it to tend to move outward by centrifugal force into position to engage the platen in the rotation of the carrier. 95
16. In a printing apparatus, the combination with the platen; of a rotating carrier, of a type lever pivoted thereto and having its weight so disposed relatively to its pivot as to cause the type lever to tend to fly outward by centrifugal force and bring the type against the platen by the movement of said carrier, said lever being pivoted at such a point as to cause the type lever to turn on its carrier so as to allow the type to be moved away from the platen by the force of its impact thereon. 100
17. In a printing apparatus, the combination with a platen, of a rotatable carrier, a character impression device pivoted on said carrier and having a tendency in the rotation thereof to move into a position in which it will strike the platen or the impression surface thereon, means for holding said impression device out of coöperating relation with the platen, an inking device consisting of an inking roller engaging with the type when the type are in inoperative position, and means for releasing said holding means. 115
18. The combination of the rotating carrier, the plurality of selecting devices carried thereby, each comprising an electro-magnetically controlled spring latch, a pivoted trip device normally engaged by said latch and constituting a type or blank space lever, terminals on said carrier en- 120 125 130

gaged by said trip devices, a circuit connected to said terminals, an electro-magnet controlled by said circuit, and carriage feeding mechanism operated by said electro-magnet.

19. The rotating carrier with trip devices pivoted thereon and acting by centrifugal force and by rebound from an obstruction as described in combination with means for holding said trip devices against centrifugal action, and cushion devices to check the rebound of the trip devices.

20. In a printing apparatus, the combination of oppositely polarized armature devices mounted on rotating supporting means, character and space-selecting devices governed by said armature devices, electro-magnetic controlling means for said armature devices; and means for receiving selective

impulses of opposite polarity and sending them through said magnet.

21. In a printing apparatus, the combination of a rotating carrier, two sets of oppositely polarized armatures thereon, character and space-selecting devices controlled by said armatures, two sets of magnets for the respective armatures, distributor contacts on the cylinder and circuit connections thereto to put a controlling circuit in communication successively with the magnets, and to simultaneously energize magnets which are operative upon armatures of opposite polarity, substantially as and for the purpose set forth.

MILTON T. WESTON.
